UNITED STATES PATENT OFFICE.

WILBUR L. WRIGHT, OF FULTON, NEW YORK, ASSIGNEE TO OSWEGO FALLS CORPORATION, OF FULTON, NEW YORK, A CORPORATION OF NEW YORK.

HOOD CAP FOR CONTAINERS.

Application filed October 2, 1923. Serial No. 666,160

This invention relates to exteriorly capping bottles and other containers, and the objects and nature of the invention will be readily understood by those skilled in the art in the light of the following description of the accompanying drawings that illustrate what I now believe to be the preferred mechanical expression or embodiment of my invention from among other forms, constructions and arrangements within the spirit and scope of my invention.

An object of the invention is to provide for exteriorly covering the mouths of bottles and other containers by hood caps of paper or like material secured by paper or like material that is removable from the bottle mouth either separately or with the cap.

With this and other objects in view, my invention consists in certain novel features in construction, and in combinations or arrangements as more fully and particularly set forth and specified hereinafter.

Referring to the accompanying drawings:

Fig. 1 shows in side elevation the mouth portion of a container exteriorly capped in accordance with my invention.

Fig. 2 shows in side elevation the mouth portion of a container exteriorly capped in accordance with my invention, the cap skirt and securing means being shown contracted under the exterior rim or shoulder of the container.

Fig. 3 is a side elevation of the paper material hood cap before application to the container mouth.

Fig. 4 is a detail side elevation of the paper material binding or securing ring before application to the hood cap on the container mouth.

Figs. 5 and 6 are top plan views of the ring.

Fig. 7 shows the structure of Fig. 1 in vertical section.

Fig. 8 shows the structure of Fig. 2 in vertical section.

The hood cap is composed of suitable flexible paper or paper board or the like, and per se can be of the common construction now found on the market, having the annular depending skirt 1, and the flat central usually circular top 1^a, that is usually im-

printed or otherwise provided with display advertising, reading or other intelligible 55 indicia.

These caps are preferably drawn from flat paper sheets by the use of dies to produce the caps with the flexible annular skirts or flanges that flare or enlarge in diameter 60 downwardly so that the caps can be nested for packing and shipment, and so that the caps can be quickly and easily applied to and over the container mouths with the cap skirts depending at the exteriors of said 65 mouths surrounding and extending below the exterior rims or shoulders of the container mouths.

The caps are designed to fit down on the top edges of the container mouths and more 70 or less snugly fit the outer surfaces of the portions of the container rims of greatest external diameters.

The caps may or may not be waterproofed, 75 waxed or otherwise treated, and the annular cap skirts are usually unbroken or continuous, but, if so desired, can be formed with spaced vertical or longitudinal slits to facilitate the contraction of the skirts to the bottle necks under the rims or shoulders, without the formation of pronounced ridges or corrugations.

According to my invention, these flexible hoods or exterior caps are secured on the container mouths by paper or like material 85 bands or rings 2 surrounding the cap skirts and holding such skirts tightly contracted to and against the container rims in such manner as to prevent accidental displacement and removal of the caps from the containers, yet permit ready removal of the cap 90 and retainer or securing band when it is desired to open the container for removal of its contents.

In the example illustrated, the securing 95 band is composed of a strong, more or less flexible, paper cylinder that in length is approximately equal to the length of the hood cap skirt, although I do not wish to so limit all features of my invention. The internal diameter of the paper band closely approximates the greatest external diameter of the rim portion of the container mouth so that when the band is forced down on the exterior 100 of the hood cap located on the container mouth, the skirt of said cap will be sur-

rounded by the band and tightly compressed and contracted against the container rim so that the cap skirt grips the rim against accidental cap removal.

5. The securing band is preferably composed of a long length of sheet paper material coiled or wound on itself with the overlying convolutions secured together so that the band is composed of several thicknesses of 10 the sheet length, one end of the length terminating at the inner surface of the band and the other at the other surface thereof.

Usually, a long sheet of paper is thus tightly wound on a mandrel to form a long 15 paper cylinder, and by appropriate means, this long paper tube or cylinder is cut into lengths, each of the dimensions to form a securing band.

The bands can be packed for storage or 20 shipment, while in cylindrical form, or can be contracted by bending at diametrically opposite points and folded flat for packing, and expanded for slipping onto the caps on the container mouths.

25. If so desired, the securing bands can be impregnated with or otherwise embody one or more suitable wax like substances rendering the bands stiff or more or less rigid at atmospheric temperatures and soft or pliable when heated.

Such bands, while heated, can be slipped exteriorly onto the hood caps located on container mouths, and the lower portions of the soft bands can then be contracted by a suitable contracting head, to contract the cap skirts tightly against the container necks under the exterior rims or shoulders of the container mouths (see Fig. 2) so that the hands which will then rapidly cool and become stiff and set, will serve to lock and seal the cap skirts to the containers under the rims thereof.

Where the stiff locking bands are thus employed, the bottle or container mouths will 45 be sealed, and, if so desired, the usually employed inner milk caps or sealing disks need not be employed. Also, where such stiff bands are employed, the hood cap cannot be removed and reapplied without detection, 50 inasmuch as the band must be torn, mutilated or so expanded as to be apparent to the eye, to permit removal of the hood cap. Usually, the bands are of a color different 55 from that of the hood caps, to display a distinctive band of color around the cap on the bottle or other container.

It is evident that various departures, 60 modifications and variations might be resorted to without departing from the spirit and scope of my invention and hence I do not wish to limit myself to the exact disclosures hereof.

What I claim is:—

65. 1. A flexible paper material hood cap having a downwardly enlarging flaring an-

nular skirt, said cap constructed and arranged to exteriorly cover the mouth portion of a milk bottle having an annular exterior rim enlargement, in combination with a cap-clamping and sealing non-expansile paper 70 material cylinder the interior diameter of which closely approximates the maximum exterior diameter of said rim enlargement, said cylinder in length approximating the length of said skirt, said cylinder being 75 multi-ply and composed of a sheet of paper material wound on itself forming secured overlying convolutions, said cylinder carrying a substance or substances rendering the cylinder normally set stiff and rigid and 80 moldable when heated, said cylinder constructed and arranged to be forced over said cap to contract the flared skirt and lock the same tightly against said rim enlargement, the lower portion of said cylinder formed to 85 be molded when hot to seal the skirt against the bottle below the maximum diameter of the bottle rim enlargement.

2. A flexible paper material hood cap having a downwardly enlarging flaring annular skirt, said cap constructed and arranged to exteriorly cover the mouth portion of a milk bottle having an annular exterior rim enlargement, in combination with a cap-clamping and sealing non-expansile 90 paper material cylinder the interior diameter of which closely approximates the maximum exterior diameter of said rim enlargement, said cylinder in length approximating the length of said skirt, said cylinder being multi-ply and composed of a sheet of paper material wound on itself forming secured overlying convolutions, said cylinder constructed and arranged to be forced over said cap to contract the flared skirt 95 and lock the same tightly against said rim enlargement.

3. A flexible paper material hood cap having a downwardly enlarging flaring annular skirt, said cap constructed and arranged to exteriorly cover the mouth portion of a milk bottle having an annular exterior rim enlargement, in combination with a cap-clamping and sealing non-expansile 110 paper material cylinder the interior diameter of which closely approximates the maximum exterior diameter of said rim enlargement, said cylinder in length approximating the length of said skirt, said cylinder constructed and arranged to be forced over said cap to contract the flared skirt and lock the same tightly against said rim enlargement.

4. A flexible paper material hood cap having a downwardly enlarging flaring annular skirt, said cap constructed and arranged to 115 exteriorly cover the mouth portion of a milk bottle having an annular exterior rim enlargement, in combination with a cap-clamping and sealing non-expansile paper material cylinder the interior diameter of 120 which closely approximates the maximum exterior diameter of said rim enlargement, said cylinder in length approximating the length of said skirt, said cylinder constructed and arranged to be forced over said cap to contract the flared skirt and lock the same tightly against said rim enlargement.

- which closely approximates the maximum exterior diameter of said rim enlargement, said cylinder in length approximating the length of said skirt, said cylinder carrying a substance or substances rendering the cylinder normally set stiff and rigid and moldable when heated, said cylinder constructed and arranged to be forced over said cap to contract the flared skirt and lock the same tightly against said rim enlargement, the lower portion of said cylinder formed to be molded when hot to seal the skirt against the bottle below the maximum diameter of the bottle rim enlargement.
- 5 5. A paper material hood cap for exteriorly covering a container mouth and its exterior rim, said cap having a flexible flaring skirt, in combination with a non-expandable paper material cylinder formed to be forced down around said skirt and bind the same tightly against the annular maximum external diameter portion of said rim sur-
- face with said cylinder extending above and below said portion of maximum diameter.
6. A container having an exterior annular rim at its mouth portion forming a downwardly facing shoulder, in combination with a paper material hood cap to cover the container mouth with the cap skirt extending down over and depending below said rim, and a non-expandable paper-material cap securing cylinder formed to be slipped down over said cap onto said skirt to tightly bind and lock the skirt against the annular exterior surface of said rim of maximum diameter, said cylinder depending below said rim and projecting above the annular portion of the rim of maximum external diameter.

In testimony whereof I have hereunto set 40
my hand at Washington, D. C., this 1st day
of October, 1923.

WILBUR L. WRIGHT.
